CLAIM

The ornamental design for a safety element for footwear, as shown and described.

DESCRIPTION

FIG. 1 is a front view of a safety element for footwear showing my new design;

FIG. 2 is a perspective view thereof;

FIG. 3 is a left side view thereof;

FIG. 4 is a right side view thereof;

FIG. 5 is a top view thereof;

FIG. 6 is a bottom view thereof;

FIG. 7 is a back view thereof;

FIG. 8 is a right side view of the safety element for footwear of FIG. 1 shown in use on a footwear article;

FIG. 9 is a left side view thereof;

FIG. 10 is a top view thereof;

FIG. 11 is a bottom view thereof;

FIG. 12 is a back view thereof;

FIG. 13 is a front view thereof; and,

FIG. 14 is a perspective view thereof.

The broken lines in the drawings show portions of the safety element for footwear as well as unclaimed environment. The broken lines and structures they depict form no part of the claimed design.

1 Claim, 14 Drawing Sheets
